ROTARY POWER-REVERSING MECHANISM

John B. Picard, Toledo, Ohio, Bruno R. Schabarum, Tulsa, Okla., and George F. Noltein, Springfield, Ohio, assignors to The National-Superior Company, Toledo, Ohio, a corporation of Delaware

Application March 17, 1934, Serial No. 716,130

9 Claims. (Cl. 74—205)

This invention relates generally to reversing mechanism for transmitting rotary power in either direction and more particularly to a unitary reversing mechanism which may be interposed between the source and the application of the power transmitted.

The invention may be conveniently applied, for example, to countershaft reversing mechanism adapted for quickly and smoothly changing the direction of the applied motion without interrupting the motion at the source of power.

As herein illustrated this invention is shown applied to a reversing counter-shaft mechanism for use with apparatus in the process of producing oil from wells.

Hoisting reels or drums are employed intermittently for relatively short intervals from the commencing of the drilling of a well until the well is producing or abandoned. The hoisting reels are generally driven by any suitable source of power through power transmitting means and it is necessary that these reels be reversed without reversing the direction of rotation of the power-driving source. However, the use of rotary power, capable of function in either direction, is not in any manner restricted to hoisting mechanism during the process of producing oil from the earth.

The reversing mechanism, as herein illustrated, is required to perform heavy duty service in reversing the direction of rotation of the mechanism under heavy loads at high speeds. In order to avoid casualties in the work as well as among the workers reversing mechanism must operate quickly and smoothly and without loss of time. Time is of the essence of some of the operations in performing this type of work as the operation may be lost and have to be repeated because its sequence was broken in time.

Another requirement of a counter-shaft reversing mechanism is that it may be adaptable for use in combination with any of several types of power source units without changes or additions to said power source units.

To these ends this invention provides novel features in the transmission means for smoothly reversing the direction of rotation of the power delivered by the mechanism and in the arrangement for supporting the power in-put and power out-put means in axial alinement and in the means for operating the reversing mechanism.

The accompanying drawings illustrate, for purposes of exemplification but without limitation of the claimed invention thereto, certain practical embodiments of the principles of this invention.

Fig. 1 is a side elevation showing one form employing the novel features of this invention.

Fig. 2 is an end view of Fig. 1.

Fig. 3 is a plan view of Fig. 1 part of which is in section showing some of the detailed parts comprising this invention and parts of which are broken away.

Fig. 4 is a plan view showing the base of the mechanism with the lever and link system for operating the forward and reversing means of the mechanism.

Fig. 5 is a detailed view partly in section of one form of the forward drive clutch mechanism.

Fig. 6 is a sectional plan view showing a modification in the shaft assembly of the reversing mechanism, parts being omitted or broken away.

Fig. 7 is a sectional plan view showing the reversing mechanism directly coupled with a power source, parts being omitted or broken away.

Referring to the drawings and more particularly to Figs. 1 to 5, 10 represents the base or frame structure having secured on its ends the upright bearing stands 11 for supporting the main bearing housings 12 which may be fastened thereto as by the bolts 13. 14 represents a shaft journaled 25 within the bearing housings 12 and retained from rotation by means of the set screws 15.

The ends of the shaft are provided with the cap plates 16 which are held in place by means of the cap screws 17 extending through the center 30 of the cap plates and entering the tapped holes in the center of the ends of the shaft. The inner peripheral surface of the cap plates engage the outer edge of the cylindrical bearing sleeves 18 preventing any outward movement thereof. The 35 bearing sleeves 18 are provided with alined clearance holes for admitting the set screw 15.

The inner edge of the bearing sleeves 18 engage the inner races 19 and 20 of the antifrictional bearings 21 and 22 which rotatably support one 40 end of the rotary driving gear or pulley member 23 and the rotary driven shaft sleeve 24 respectively.

25 represents a bearing anchor sleeve on the shaft 14 which is held from longitudinal movement by means of the set screw 26. The ends of the anchor sleeve abut the inner races 27 and 28 of the anti-frictional bearings 29 and 30 which support the other end of the pulley 23 and the sleeve 24. Thus the relative position of the pulley 23 and the sleeve 24 on the shaft 14 is fixed by the anchor sleeve 25 and the bearing sleeves 18.

The driven sleeve 24 is provided with the internal ribs 24' arranged longitudinally thereof for reinforcement of the sleeve.

The pulley 23 has secured thereto the cylindrical drum 31 provided with a smooth perimetral friction surface which is encircled by the half clutch bands 32 and 33.

5 One end of the clutch bands is provided with the strap 34 having a transverse cylindrical sleeve arranged to be pivotally mounted on the pin 35 extending from the face of the crank disc 36 on the inner end of the shaft 37 which is rotatably mounted in the conical or reverse friction drum member 38. The other end of the clutch band is provided with a pierced lug 39 arranged to receive the threaded portion of the bolt 40 which is adjustably secured thereto as by the 10 nuts and lock nuts 41. The bolt 40 is also provided with a transverse cylindrical sleeve arranged to be pivotally mounted on the pin 42 extending from the face of the crank disc 36 on the inner end of the shaft 37. The outer ends 15 of the pins 35 and 42 are held in place by the cap disc 36.

The shafts 37 are parallel to each other and symmetrically disposed on either side of the axis of the drum 38 and parallel to the latter. 20 The center of the pins 35 and 42 are eccentric to the axis of the shafts 37 as shown in Fig. 5 and when the shafts 37 are rotated the pins move the straps 34 and the bolts 40 clamping or releasing the bands in frictional engagement 25 with the cylindrical drum 31.

If the shafts 37 are rotated so as to clamp the bands onto the drum 31 the rotary pulley 23 then drives the conical drum 38 in the same direction, through the clutch band mechanism and 30 the shafts 37.

The conical drum 38 is keyed to the shaft sleeve 24 by the key 43 which is locked in place by the set screw 44. The driven gear or pulley member 45 is also keyed to the sleeve 24 by the key 46 which is locked in place by the set screws 47. Thus any rotary movement imparted to the 40 conical drum 38 drives the driven pulley 45 through the medium of the shaft sleeve 24.

45 48 represents a clutch operating sleeve splined as at 49 on the shaft sleeve 24 to permit longitudinal motion of the clutch sleeve thereon. The sleeve 48 is provided with a pair of sockets 50 to receive the ball joints 51 on one end of the connecting links 52. The ball joints 53 on the 50 other end of the connecting links 52 are arranged to be secured in their complementary sockets 54 in the lever arms 55, secured to the outer ends of the shafts 37. The clutch operating sleeve 48 is provided with the integral annular key 56 arranged to rotate in the annular groove of the stationary partible collar 57. This collar is provided with two outwardly extending and oppositely disposed ears 58 arranged to extend into the slots 59 in the ends of the bifurcated lever 60 60 61 which is pivotally supported in the stand 61 secured to the frame 10 as shown in Figs. 1, 2 and 5. Thus when the lever 60 is moved in a counterclockwise direction it carries with it the collar 57 which in turn slides the rotating clutch sleeve 65 68 to the left and longitudinally of the shaft sleeve 24. The links 52 then rotate the levers 55 and the shafts 37 in a counterclockwise direction in Fig. 5 causing the pins 35 and 42 to pull the clutch bands into frictional engagement with the cylindrical drum 31 thereby rotating the shaft sleeve 24 and the driven pulley 45 therewith. This is termed the direct or forward drive of the mechanism.

70 75 Conversely, movement of the bifurcated lever

60 in a clockwise direction in Fig. 1 will disengage the clutch bands from the drum 31.

As herein illustrated the reverse drive of the mechanism is attained by the use of the frusto-conical rollers 62 which in this case performs the dual function of a clutch and a gear element for reversing the mechanism. 63 represents a frusto-conical face on one side of the driving pulley 23 adjacent the periphery thereof which is, in this instance, provided with the frictional lagging 10 material 64 arranged to engage the conical surface of the rollers 62. The rollers 62 may be composed of laminated material to insure long and uniform wearing qualities well known in the friction pulley art. 65 represents the conical 15 surface of the drum 38 which is also arranged to be engaged by the rollers 62. Thus the rotary driving pulley 23 may be made to drive the drum 38 and the driven pulley 45 on the shaft sleeve 24 in the reverse direction when the frusto-conical rollers 62 are moved into engagement with the conical frictional surfaces on the pulley 23 and the drum 38.

The rollers 62 are rotatably supported by the anti-frictional bearings 66 on the non-rotary 25 spindle 67 whose axes are in this instance disposed at any angle substantially 45 degrees to the shaft 14 and in the same horizontal plane.

68 represents a cap plate on the inner end of the spindle 67 arranged to hold the inner races 30 of the bearings 66 and the spacing sleeve 69 against the shoulder 71 on the shaft. 70 represents a hub-cap arranged to close the bore of the inner face of the rollers 62 to prevent dirt and other foreign matter from entering therein. 35

From the shoulders 71 to the shoulders 72 the spindles are cylindrical and from the shoulders 72 the outer ends of the spindles are square in cross section as shown in Fig. 1 at 73. The square end portion of each spindle is slidably 40 supported in the upwardly open squared bearing slot 74 in the bearing box 75 carried by the upright stand 76 whose lower ends are secured to the base frame 10. The bearing slot 74 is arranged to be closed at the top by the plate 77 45 bolted to the bearing box. The slot 74 is wider than the squared portion 73 of the spindle, permitting it to move transversely therein.

78 represents helical springs carried within suitable openings 79 in the vertical face, of the 50 squared portion 73 of the spindle, that is remote from the driving pulley 23. The ends of the springs are provided with the mushroom headed pins 80 whose outer faces bear against the vertical wall 81 of the slot 74. The pressure of the 55 springs acts on the pins 80 to move the spindle 67 away from the vertical wall 81. The transverse movement of the spindle 67 is limited by the plates 82 on the ends of the adjusting bolts 83 which pass through tapped holes in the wall 83 60 of the bearing housing 75. Thus when the spindle 67 is moved inwardly to engage the roller 62 with the conical friction surfaces, the roller first contacts the frictional driving surface 64 of the rotary pulley 23 and is thereby rotated. 65 Further inward movement of the spindle 67 forces the rotating roller 62 up the conical surface 64 moving the axis of the spindle transversely of the bearing and compressing the springs 78 until the roller engages the conical friction surface 65 on 70 the drum 38 thereby driving the shaft sleeve 24 and the driven pulley 45 in the reverse direction as long as the rollers are thus held in engagement with their complementary frictional surfaces. When the rollers 62 are in their full meshed posi- 75

tion and conical friction surfaces extend to form a complete cone they would meet at an apex on the axis of the shaft 14 which precludes any possibility of sliding friction between the faces of 5 the contacting elements.

The spindles 67 are moved longitudinally of their axis by means of the vertical levers 84 pivotally supported at 85 on the stands 76. The upper ends 86 of the levers 84 are bifurcated to fit 10 around the spools 67 adjustably secured to the ends of the squared portion 73 of the spindles. The lower ends of the levers 84 are pivotally attached to the adjustable connecting rods 88 which extend through the guides 89 and are pivotally attached at their other ends to the bell cranks 90 15 pivoted to a bracket on the cross member of the base 10 as shown in Fig. 4. The other ends of the bell cranks are connected by the short links 91 to the cross pin 92 which is supported by the lower bifurcated end 93 of the forward clutch 20 lever 60. The trifurcated head 94 on the end of the link 95 is provided with alined holes to receive the pin 92 and is arranged so that its center fork is between the bifurcated ends of the lever 60. The links 91 are outwardly adjacent thereto and 25 the outer forks of the head 94 are on the ends of the pin as shown in dotted lines in Fig. 4.

The other end of the link 95 is pivotally attached to the bell crank 96 pivoted at 97 on the frame 10 and having its other end connected by the rod 98 to the hand operating lever 99.

When the lever 99 is moved to the left, as in Fig. 2, the forward clutch lever 60 will be operated in a clockwise direction disconnecting the 30 forward clutch drive and at the same time the bell crank 96 will be operated in a counterclockwise direction in Fig. 4, thereby rocking the reverse lever 84 to move the rollers 62 into engagement with their complementary faces to operate the 35 driven pulley 45 in the reverse direction. When the hand operating lever is in its neutral position the linkage system is arranged to permit the driving pulley 23 to rotate alone.

Referring to Figs. 1, 2 and 3, 100 represents a 40 brake drum secured to the shaft sleeve 24 by the key 101. The perimetral surface of the brake drum is grooved to receive the brake band 102 supported from below on the pin hinge 103 secured in the bracket 104 bolted to the cross member 105 of the bearing stand 11. The brake is operated by the ordinary brake rod 106 and cammed lever 107 arranged, when pulled to the right in Fig. 2, to shorten the bolt 108 to draw the ends 109 of the band together, gripping the drum 50 to slacken the speed or stop the rotation of the driving pulley 45.

Referring to the modification shown in Fig. 6, wherein the elements similar to those described above are designated by the same reference 60 numbers, 110 represents the reversing mechanism supporting shaft which, unlike the former instance, is rotatably supported in the bearing housings 12. The right hand end of the shaft 110 extends through the bearing housing 12 and has 65 secured thereto the universal joint 111 that connects the shaft directly to the hub 112 arranged to hold a fly-wheel on the shaft 113. In place of the driving pulley 23 the shaft 110 has keyed thereto, as at 114, the forward and reverse friction 70 drum member 115 having the conical friction surface 63 arranged to engage the roller 62 for reversing the mechanism. This pulley also carries the cylindrical clutch drum 31 arranged directly to drive the pulley 45 in the forward direction as before.

Owing to the fact that the shaft 110 is designed to rotate, antifrictional roller bearings cannot be used as they would be stationary relative to the rotating shaft and shaft sleeve 24 and their line contact would peen into the races 5 ultimately causing their destruction. It is therefore necessary to use the sleeve type of bearing 116 for rotatably supporting the drive shaft sleeve 24 to avoid this difficulty.

The modification shown in Fig. 7 illustrates 10 the use of a stationary or dead shaft 117 in combination with a rotary power shaft 118 for the reversing mechanism. In this instance the rotary power shaft 118 may be directly connected to or be a part of the shaft of the power mechanism. This shaft extends through the bearing housing 12 and has keyed thereto at 119 the fly-wheel 120. The face of the hub portion 121, remote of the bearing housing 12, is provided with the annular toothed key portion arranged to 15 mesh with the complementary toothed key portion 122 on the adjacent face of the forward and reverse friction drum member 123.

The drum 123 is rotatably supported by the antifriction roller bearing 124 and the antifriction ball bearing 125 which are carried by the dead shaft 117 and the rotary power shaft 118 respectively. Thus the free end of the dead shaft 117 is journaled in the drum 123 which is coaxial with the shaft 117 and is universally coupled to 20 the fly-wheel 120 and the shaft 118 and any slight variation in alinement of the dead shaft 117 is thereby compensated for.

The adjacent ends of the shafts 117 and 118 are provided with the bearing retained caps 126 25 which may be bolted or fastened thereto in any suitable manner.

The forward friction drum portion 31 of the drum 123 is provided with the spoke or webs 127 which serve to strengthen the drum 123 to permit it to carry the journaling load of the dead shaft 117.

The forward and reverse driving mechanism in this modification and the operation thereof is the same as that described for Figs. 1 to 5 and 45 will therefore not be repeated.

While this invention has been illustrated and described particularly in reference to a counter-shaft reversing mechanism for use with well drilling and pumping apparatus, it should be understood that changes may be made in the form disclosed, without departing from the spirit of the invention and that certain features may sometimes be used to advantage without a corresponding use of other features.

We claim:—

1. In a rotary reversing mechanism, the combination of a power-rotated shaft, a stationary shaft alined therewith, a member rotatably mounted on the adjacent ends of said shafts, 60 means to connect said member for rotation with the first shaft, a pulley rotatable on the stationary shaft, and selective means for connecting said pulley to said member for rotating said pulley in either direction.

2. In a rotary reversing mechanism, the combination of a power-rotated shaft, a stationary shaft alined therewith, a member rotatably mounted on the adjacent ends of said shafts, means to connect said member for rotation with 70 the first shaft, a pulley rotatable on the stationary shaft, and selective means for connecting said member to said pulley for rotating the pulley in either direction, and ball bearings interposed between the member and one shaft and 75

roller bearings interposed between the member and the other shaft to provide for universal movement between the shafts.

3. In a rotary reversing mechanism, the combination of a rotary member arranged to receive power from a suitable source and provided with a concentric conical surface, a second member coaxial therewith and also provided with a concentric conical surface, rollers movable axially to engage said surfaces for rotating the second member from the first member, and means for causing said rollers to first engage the surface of the first member as they are moved axially to engage said members.

15 4. In a rotary reversing mechanism, the combination of a rotary member arranged to receive power from a suitable source and provided with a concentric conical surface, a second member coaxial therewith and also provided with a concentric conical surface, conical rollers arranged to be moved axially into engagement with said conical surfaces to impart rotation to the second member, and means whereby said rollers first engage the first member.

25 5. In a rotary reversing mechanism, the combination of a rotary member arranged to receive power from a suitable source and provided with a concentric conical surface, a second member coaxial with the first member and also provided with a concentric conical surface, and rollers movable axially to engage said surfaces for rotating the second member from the first member, and means for moving the rollers laterally to first engage the surface of the first member.

35 6. In a rotary reversing mechanism, the combination of a rotary member arranged to receive power from a suitable source and provided with a concentric conical surface, a second member coaxial with the first member and also provided with a conical surface, conical rollers arranged to be moved axially into engagement with said conical surfaces to impart rotation from the first member to the second member, and means for moving said rollers laterally to cause them to first engage the conical surface of the first member.

7. In a rotary reversing mechanism, the combination of a stationary shaft, a driving member and a driven member both rotatably mounted on said shaft and held against axial movement, a pair of annular driving surfaces on one side of the driving member, a contractible band on the driven member arranged to engage one of the driving surfaces of the driving member for im-

parting the same rotational movement to the driven member, an annular driven surface on the driven member corresponding to the other driving surface of the driving member, said driving and driven surfaces being held against axial movement rollers arranged for axial movement to engage said last mentioned surfaces for imparting reverse rotation to the driven member when the contractible band is out of engagement with the driving member and means for contracting said band and for moving said rollers axially.

8. In a rotary reversing mechanism, the combination of a stationary shaft, a driving member and a driven member both rotatably mounted on said shaft and held against axial movement, a pair of annular driving surfaces on one side of the driving member, a contractible band on the driven member arranged to engage one of the driving surfaces of the driving member for imparting the same rotational movement to the driven member, an annular driven surface on the driven member corresponding to the other driving surface of the driving member, said driving and driven surfaces being held against axial movement rollers arranged for axial movement to engage said last mentioned surfaces for imparting reverse rotation to the driven member, and means for operating said band and said rollers, said means being controlled from a common source preventing their simultaneous operation.

9. In a rotary reversing mechanism, the combination of a stationary shaft, a driving member rotatable thereon and held against axial movement, said driving member having on its face a conical driving surface and a cylindrical driving surface concentric therewith, a driven pulley rotatable on said shaft adjacent to said face of the driving member and held against axial movement, said driven pulley provided with a conical surface opposed to the conical driving surface of the driving member and also provided with clutch means arranged to engage said cylindrical driving surface whereby to rotate the driven pulley in unison with the driving member said driving and driven surfaces being held against axial movement and means arranged to be interposed between said conical surfaces whereby to rotate the driven pulley in the opposite direction.
